UNITED STATES PATENT OFFICE.

FERNANDO SEVIDAL BERNABÉ, OF MALASKI, PHILIPPINE ISLANDS.

COMBINATION CANE AND GUN.

Application filed May 13, 1925. Serial No. 30,016.

To all whom it may concern:

Be it known that I, FERNANDO SEVIDAL BERNABÉ, a citizen of the United States, residing at Malaski, Pangasinan, Philippine Islands, have invented certain new and useful Improvements in Combination Canes and Guns, of which the following is a specification.

The present invention appertains to a combination cane and gun and has for its principal object to provide a device of this nature possessing a very simple and efficient construction, one which is easy to handle and manipulate, reliable, inexpensive to manufacture, strong, durable and well adapted to the purpose for which it is designed.

With the above and other objects in view as will appear as the description progresses, the invention resides in certain novel features of construction, in the combination and arrangement of parts as will be hereinafter more fully described and claimed.

In the drawing:

Figure 1 is an elevation of the device embodying the features of my invention,

Figure 2 is a fragmentary longitudinal section taken therethrough,

Figure 3 is another longitudinal section therethrough being taken at right angles to that shown in Figure 2 and showing the parts extended,

Figure 4 is a transverse section taken on the line 4—4 of Figure 3,

Figure 5 is a transverse section taken on the line 5—5 of Figure 2,

Figure 6 is a detail perspective view of the hammer housing showing a portion thereof in longitudinal section,

Figure 7 is a detail perspective view showing the casing in section with the barrel extended therefrom, the latter also being shown partly in section,

Figures 8 and 9 are transverse sections taken on the line 8—8 and 9—9 respectively of Figure 2, and

Figure 10 is a detail perspective partly in section showing a portion of the barrel and housing.

Referring to the drawing in detail it will be seen that the outer casing is formed in sections 1, 2 and 3. The section 1 has fixed thereto a handle 4. All of the sections 1, 2 and 3 are of hollow tubular construction.

A cylinder or tube 5 is situated in sections 1 and 2 and another tube 6 is situated with-

in tube 5. The section 1 and tubes 5 and 6 are held together by a transversely extending screw 7. A barrel 8 is slidably mounted in tube 6. This barrel is provided with a bayonet slot 9 including the slot proper 10 and offset notch 11. An opening 12 is provided in the barrel 8 for the insertion of a cartridge and a rib 13 provided inside of the barrel adjacent the opening 9 for engaging the flange as is indicated at 14 of an ordinary cartridge 16. This barrel 8 extends into section 3 and is fixed thereto in any suitable manner. A hammer housing 16 is mounted within the barrel 8 and the enlargement 17 thereof extends through the bayonet slot and is fixed to the tube 6 by screws 18. When the device is assembled as shown in Figure 2 it is necessary to rotate section 3 and barrel 8 so as to move the notch 11 out of engagement with the enlargement 17, thus placing it in registry with the slot proper 10 in order that the barrel may be moved so that the opening 12 is accessible for inserting a cartridge, the extended position being shown to advantage in Figure 3 of the drawings. An extension 20 is provided on the forward end of the hammer housing 16 for engaging the cartridge 15 to hold its flange in engagement with the rib 13. A hammer 21 is slidably mounted within the housing 16 and is provided with an elongated shank 22 having a head 23 at its end. A spring 24 is mounted on the shank between the restricted end 25 of the housing and the enlargement 26 on the hammer 21 and tends to force the hammer 21 in engagement with the cap of the cartridge 15 when said hammer is released.

The trigger mechanism consists of a block 26 disposed within the barrel 8 at the end adjacent the handle 4 being fixed therein by screw 27. The forward end of this block is provided with a recess 28 for receiving the head 23 and a catch 29 is pivoted on the block the hooked end 30 thereof being adapted to engage the head 23. A spring holds the hooked end 30 normally in engagement with the head 23 or so as to engage it as will be more fully explained hereinafter. A trigger 31 is slidably through section 1 and tubes 5 and 6 to engage the end of the catch 29 so that by pressing in upon the trigger the hooked end thereof may be disengaged from the hammer head 23 so that the hammer may move quickly

forward being impelled by spring 24 to engage the cap of the cartridge 15 and fire the same.

When the device has been extended to the holding position shown in Figure 3 and the cartridge placed therein as previously explained the barrel is moved inwardly of tube 6 until section 3 engages band 35 at the end of section 2 and then the section 3 and barrel 8 are rotated so that the notch 11 of the bayonet slot 9 will be engaged with the enlargement 17 of the hammer housing 16. As the barrel is being moved inwardly of the tube 6 it will be noted that the catch 29 will cock the hammer 22 because when the barrel has been moved to its extended or outwardly disposed position the catch is brought into engagement with the head 23 of the hammer.

It is thought that the construction and operation of the invention will now be clearly understood without any more detailed description thereof. It is desired, however, to point out that numerous changes in the details of construction, and in the combination and arrangement of parts may be resorted to without departing from the spirit or scope of the invention as hereinafter claimed or sacrificing any of its advantages.

Having thus described my invention, what I claim as new is:

1. A device of the class described including a casing formed in sections, a barrel extended into both sections being slidable in one and fixed to the other, a hammer hous-

ing disposed within the barrel, and provided with an enlargement, said barrel provided with a bayonet slot for receiving the enlargement at the housing, means for fixing the enlargement of the housing to the casing, a hammer in the housing, means in the barrel for engaging one end of the hammer, a spring associated with the hammer, and means for releasing the hammer. 45

2. A device of the class described including a casing, a barrel slideable and rotatable in the casing and extending therebeyond, said barrel provided with an opening in order that a cartridge may be inserted 50 therein, an annular internal ridge provided adjacent the opening in the barrel for receiving a flange of a cartridge inserted through the opening, said barrel provided with a bayonet slot, a hammer housing disposed within the barrel and having an enlargement extending through the bayonet slot, means for fixing the enlargement to the casing, a spring actuated hammer within the housing and having a head at one 55 end, an extension on the housing adapted to engage the cap end of a cartridge when inserted in the barrel and when the notch of the bayonet slot is engaged with the enlargement, and a trigger mechanism at one 60 end of the barrel fixed thereto for engaging the head all in the manner and for the purpose specified. 65

In testimony whereof I affix my signature.

FERNANDO SEVIDAL BERNABÉ.
